UNITED STATES PATENT OFFICE.

GUY B. HUMES, OF CHICAGO, ILLINOIS.

HORN-MUTE.

1,387,490.

Specification of Letters Patent.

Patented Aug. 16, 1921.

Application filed August 16, 1920. Serial No. 403,636.

To all whom it may concern:

Be it known that I, GUY B. HUMES, a citizen of the United States, and a resident of the city of Chicago, county of Cook, and 5 State of Illinois, have invented certain new and useful Improvements in Horn-Mutes, of which the following is a specification.

My invention relates to horn mutes and has for its primary object the construction 10 of a horn mute of such provision as to enable the user to vary the volume and tone of a horn in which my invention is positioned.

Other objects will appear hereinafter. 15 The invention consists in the combinations and arrangements of parts hereinafter described and claimed.

The invention will be best understood by reference to the accompanying drawings 20 forming a part of this specification, and in which,

Figure 1 is a sectional view of a portion of a horn with my invention positioned therein.

25 Fig. 2 is an end view showing the adjustable feature, and

Fig. 3 is a cross sectional view along the line 3—3 of Fig. 2.

The preferred form of construction comprises a hollow conical shaped papier-mâché member 1, having a metallic reinforcement 2 surrounding the inner periphery of the smaller opening. Fixedly mounted in the larger end of said conical member is a closure member 3, said closure member having orifices 4 and 5, said orifices having straight 30 parallel sides and curved ends cut or stamped therein and a semi-circular bearing plate 6 mounted thereon. Fixedly mounted on the inner side of said closure member 3 is a circular papier-mâché member 7, having circular orifices stamped or cut 35 therein, said orifices being in alinement with the orifices of the closure member 3. Fixed to the face of the member 7 is a smaller circular papier-mâché member 8, having circular orifices cut or stamped therein, said orifices being in alinement with the orifices in the members 3 and 7 and fixedly mounted 40 on the inner side of the member 8 is a circular flexible member 9, said flexible member 9 having orifices therein alined with the orifices in the member 8.

Movably positioned and firmly pressing 50 against the flexible member 9 is a circular

metallic disk 10, said disk having orifices therein, and said orifices being adapted to aline with the orifices heretofore mentioned when the disk is revolved to a certain position. The metallic disk 10 is held in position within the mute by means of a shaft 11 which passes through the axes of the members 3, 7, 8, 9 and 10, whereupon it is bent in a lateral direction and fixed to the inner face of the member 10 so that a rotation of the shaft 11 will cause the disk 10 to rotate. The opposite end of the shaft 11 is bent in a lateral direction forming an adjustment arm 12, said adjustment arm having its outer extremity bent to form a finger grip 13, the inner side of which is adapted to frictionally engage the semi-circular bearing plate 6.

Mounted on the member 8 in the orifices are felt washers 14 and on the flexible washers are skin vibrators 15, said skin vibrators being clamped into position by means of perforated metallic closure members 16, said closure members being circular metallic disks having one straight side and having a portion bent in a lateral direction to form lugs 17. The circular portion of the closure members 16 is adapted to be inserted under one of the straight sides of the orifices in the member 3, alining the straight side of the closure with the opposite straight side of the orifices. The closure member is then pressed firmly against the vibrators and turned a quarter revolution by means of the lugs 17, thus locking said closure member between the members 3 and 7.

Mounted on the exterior of the mute are cork wedge members 18, said cork wedge members being adapted to bear against the inner periphery of the horn and hold the mute firmly positioned therein.

The device is adapted to be placed in the horn as heretofore mentioned and mutes said horn in a manner as previously described. When it is desired to increase the volume of the horn and to produce the so-called "jazz" tones, the inner disk is revolved by means of the arms 12 until the alined orifices are more or less in alinement, the more in alinement they are the greater the volume of tone and vice versa.

While I have illustrated and described the preferred form of construction for carrying my invention into effect, this is capable of variation and modification without depart-

ing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:—

- 10 1. An article of the class described, comprising a hollow conical shaped member; a closure member mounted in one end of said conical shaped member orifices in said closure member; and means mounted thereon whereby the volume of the tone of the horn is varied, substantially as described.
- 20 2. An article of the class described, comprising a hollow conical shaped member; a closure member mounted in one end of said conical shaped member orifices in said closure member; and means whereby said orifices are closed and opened to produce a variable tone, substantially as described.
- 25 3. An article of the class described, comprising a hollow conical fibrous member enclosed at the larger end; orifices in said enclosed end and means whereby said orifices are adjustably regulated to produce a greater or lesser volume of tone, substantially as described.
- 30 4. An article of the class described, comprising a hollow conical shaped member enclosed at the larger end; orifices in said enclosed end; vibrators mounted in said orifices; and means whereby said orifices are adjustably regulated to produce a greater

or lesser volume of tone, substantially as described.

5. An article of the class described, comprising a hollow fibrous conical shaped member inclosed at the larger end; orifices in said inclosed end; vibrators mounted in said orifices; a rotatable disk mounted on the inner face of said closure member; orifices in said disk adapted to align with the orifices in the closure member upon rotation of said disk, substantially as described.

6. An article of the class described, comprising a hollow fibrous conical shaped member, closed at the larger end and open at the smaller end; reinforcing means mounted within the smaller open end; orifices in the closed end; vibrators mounted in said orifices; circular disks having orifices aligned with the orifices within the closed end mounted on the interior face of said closed end; a leather washer mounted on the interior face of said disks; orifices in said washer aligned with the orifices in said disks; a metallic disk rotatably mounted on the leather washer; orifices in said disk adapted to align with the orifices in the washer and exterior disks upon rotation of the metallic disk, substantially as described.

In testimony whereof I have signed my name to this specification in the present of two subscribing witnesses.

GUY B. HUMES.
